ENGINE STARTER

Walter L. Gorden, Chicago, Ill., assignor to Mall
Tool Company, Chicago, Ill., a corporation of
Illinois

Application July 7, 1941, Serial No. 401,339

8 Claims. (Cl. 123—185)

My invention relates to engine starting mechanisms for imparting rotative motion to a shaft, such as the crank shaft of an internal combustion engine.

The general object of my invention is to eliminate some of the undesirable features of engine starters already on the market.

In an engine starting device of the type which employs the use of a rewind spring to reverse the rotation of the engine starter shaft, difficulty has been encountered in maintaining the crank shaft engaging portion of the engine starter out of engagement with the crank shaft during reverse rotation of the starter shaft. One object of my invention is to overcome this difficulty.

Another difficulty encountered in the spring rewind type of starter is to maintain the crank shaft engaging portion of the engine starter out of engagement with the crank shaft while the engine is running thereby eliminating unnecessary noise and wear on parts. The importance, however, of overcoming this particular difficulty is emphasized when the engine is turned off. Frequently when an engine is turned off and the crank shaft approaches a standstill, the engine "backfires" and causes an abrupt reverse rotation of the crank shaft. When this occurs, it is essential that the crank shaft engaging portion of the engine starter be in a disengaged position relative to the crank shaft so as to prevent destruction of mechanical parts. Another object of my invention is to overcome this difficulty.

A further object of my invention is to provide an engine starter which is a complete unit in itself and may be detached from the engine if desired.

Another object is to eliminate the necessity of accurate balancing and aligning of parts such as is necessary in most starters now on the market.

Still another object of my invention is to provide an auxiliary starter pulley which can be used to start the engine if the engine starter is removed and which can also be used as a belt takeoff for running an auxiliary attachment.

Other objects and advantages will become apparent upon examination of the following specification and upon examination of the drawings in which:

Fig. 1 is a sectional view of my engine starting device; 50

Fig. 2 is a plan view taken on line 2—2 of Fig. 1;

Fig. 3 is a plan view of a modified form of my invention taken on the same plane as Fig. 2; 55

Fig. 4 is a fragmentary sectional view taken on line 4—4 of Fig. 3 but in the same plane as in Fig. 1;

Fig. 5 is a plan view of another modified form of my invention taken on the same plane as Fig. 2;

Fig. 6 is a fragmentary sectional view taken on line 6—6 of Fig. 5 but in the same plane as Fig. 1; and

Fig. 7 is a fragmentary enlarged sectional view of the leaf spring as shown in Fig. 1.

In the preferred embodiment of my invention as shown in Figs. 1, 2 and 7, I have shown an engine starting device having a main casing A, a starter assembly B and an engine shaft C.

The casing A is preferably rigidly but removably secured to the main engine housing by means of screws extending through the annular shoulder 2 and threaded into the engine housing (not shown). The casing A is provided interiorly with an annular rib 3 which forms a container for the rewind spring 4. The rewind spring 4 which is similar to a clock spring is conventional in engine starters and comprises a spirally wound spring fastened at one end to the rib 3 and at its other end to a rotatable collar 5. A thin metal disc 6 forms a cover for sealing the spring 4 within the container defined by the annular rib 3. A rope starting pulley 7 is mounted on the diametrically reduced extension of collar 5 and a nut 8 securely holds the pulley 7 against the annular shoulder 9 on collar 5. The pulley 7 may be keyed to the collar 5 so as to assure rotation along therewith. A sleeve 10 is pressed into a bore in hub 11 so as to be stationary and so as to provide an axle upon which collar 5 is free to rotate. The bolt 12 with its head 13 serves to prevent axial displacement of the starter parts including spring 4, collar 5, and pulley 7. The length of the sleeve 10 is such that it extends .004 or .005 inch beyond the inner end of collar 5 so that collar 5 will be free to rotate on the sleeve 10 when head 13 is tightened against the hub 11.

45 The starter pulley 7 is provided with a starter rope 14 which is secured at its inner end to the pulley. A handle 15 is secured to the other end of the pulley rope for manually pulling the starter rope.

The free end of the engine shaft extends through a flywheel 16 and an auxiliary starting pulley 17 is secured to the flywheel with bolts 18. If desired the entire starter mechanism can be removed by loosening the screws which fasten casing A to the engine housing. Auxiliary pulley

17 can then be used to start the engine or it can be used as a belt takeoff for running an auxiliary attachment. The mechanism which establishes engagement between the starting mechanism and the engine shaft or crank shaft C consists of a ratchet wheel 19 secured concentrically to the auxiliary pulley 17 by screws 20 and a pawl 21 secured to pulley 7 so as to be rotatable therewith. The pawl 21 has a single tooth 22 which may engage any of the teeth on ratchet wheel 19. The pawl is pivotally mounted on pulley 7 by means of pivot pin 23. The pulley 7 is provided with a lug portion 24 as best shown in dotted lines in Fig. 2 for accommodating pivot pin 23. A leaf spring 25 is secured to the upper end of the pawl lever 21 and is biased against the face of an annular shoulder or flange 26 in the casing A. A lug 33 secured to the face of pulley 7 acts as a stop to limit movement of pawl 21 about its pivot pin 23.

I have also provided a spring mechanism consisting of a compression spring 27 received in a bore 28 in a side face of pawl lever 21. A lug 29 secured to the face of pulley 7 has a bore 30 receiving the other end of the compression spring 27. Said spring 27 urges the pawl lever 21 in counter-clockwise direction about pivot pin 23 as viewed in Fig. 2.

Method of operation

In starting an engine with the device of my invention as shown in Figs. 1, 2 and 7 one has only to grasp the handle 15 and exert a manual pull in a direction away from the casing A.

This causes the pulley rope to unwind and the pulley 7 to turn in engine starting direction. The moment the pulley 7 starts to rotate in engine starting direction (counter-clockwise as viewed in Fig. 2), the frictional resistance set up as a result of the spring 25 being biased against the face of shoulder 26 causes the pawl lever to rotate in clock-wise direction about its pivot pin 23. The tooth 22 engages one of the teeth on ratchet wheel 19 and the continued rotation of the pulley 7 causes the engine shaft to be turned, thereby starting the engine. When the engine starts, the R. P. M. of the engine shaft exceeds the R. P. M. of the pulley 7 and the ratchet wheel consequently overruns the pawl and kicks the pawl tooth 22 out of engagement with the teeth of the ratchet wheel.

Likewise the moment the engine starts running the operator releases the manual pulling of the starter rope 14 and the spring 4 causes the starter rope to be recoiled on the pulley 7. It is to be understood that when the starter rope is manually pulled so as to unwind and cause pulley 7 to rotate in engine starting direction, the spring 4 is simultaneously caused to coil up under tension and when the manual pulling of starter rope 14 is released, the spring 4 unwinds thereby reversing the rotation of pulley 7. The moment pulley 7 begins to reverse its direction of rotation the frictional resistance set up as a result of spring 25 being biased against the face of shoulder 26 causes the pawl lever to rotate in counter-clockwise direction about its pivot pin 23 until it engages the lug 33.

The frictional resistance set up between spring 25 and shoulder 26 is always present and it maintains the pawl lever in its retracted position against the lug 33 all during the time the engine is running and when the engine stops running and a "backfire" occurs causing a reversal of rotation of the engine shaft, there is no damage

done to pawl 21 because it is maintained in its retracted position as shown in Fig. 5.

In order to positively assure that the pawl lever 21 will be maintained in the retracted position as shown in Fig. 5 during the time the engine is running, I have provided the spring 27, heretofore described. The spring 27 is normally under compression at all times, even when the pawl lever is in its retracted position as shown in Fig. 5, and the function of the spring is to maintain the pawl lever in its retracted position during the time the engine is running.

It can be seen however, that the spring 27 is not essential but is merely auxiliary to the spring 25. The spring 25 also serves the function of maintaining the pawl lever 21 in retracted position during the time the engine is running. It is to be understood that the tension exerted by spring 27 is only slight and does not interfere with the functioning of spring 25 in causing engagement and disengagement of pawl 21 with ratchet wheel 19. The frictional resistance set up between spring 25 and shoulder 26 is sufficient to overcome the tension of spring 27.

It is to be noted that the periphery 31 at the outer end of spring 25 defines an arc which is generated from the axis of the pivot pin 23 thereby assuring that the periphery of said spring cannot bind or jam against the interior wall 32 of casing A when the pawl lever is rotated about pivot 23. It is also to be noted that the stop lug 33 serves to prevent the pawl lever from rotating too far in counter-clockwise direction thereby assuring that the outer end of spring 25 cannot slide off of shoulder 26.

Beneath the head of bolt 23 I have provided a washer 35 which is of sufficient diameter to provide a substantial bearing surface for the side wall of pawl lever 21. Also the lug portion 24 on pulley 7 provides a substantial bearing surface for the opposite side wall of pawl lever 21. The reason for providing considerable bearing surface for the side walls of pawl lever 21 is to eliminate side "play" of the pawl lever. It can be seen that if the pawl lever had any side play, the frictional resistance or amount of bias set up between spring 25 and shoulder 26 could not be controlled satisfactorily. To further assist in the elimination of side play of the pawl lever, I have provided said pawl lever with a bearing shaft 61 extending through a bore in the lug portion 24 of pulley 7. By controlling this side play the tendency of the pawl lever to bind when rotating about pivot pin 23 is eliminated.

In the modified form of my invention as shown in Figs. 3 and 4 I have shown a "floating" ring 37 mounted in an annular channel 38 in the interior wall of casing A. The ring is assembled into the channel by squeezing the free ends 40 together and reducing the diameter of the ring so that it may be forced into the annular channel. Approximately diametrically opposite the free ends 40 of ring 37 I have formed a loop portion 41 in the ring which is slidably received in a recess 42 shaped correspondingly to the shape of the loop. The recess 42 is in the upper end of the pawl lever 21a. The ring 37 is rather loosely mounted in channel 38 so that some frictional resistance is set up when the ring is rotated within the channel. The pawl lever 21a is actuated into and out of engagement with the ratchet wheel 19a in the same manner as heretofore described with respect to Figs. 1, 2 and 7, with the ring 37 serving to set up the necessary frictional resistance within channel 38 for oscillating the pawl

lever about its pivot 23a. The stop lug 33a limits retractive movement of the pawl lever to prevent the loop portion 41 from becoming disengaged from the recess 42.

In the modified form of my invention as shown in Figs. 5 and 6 I have shown another type of "floating" ring 51 which is loosely mounted in the channel 52 which channel is formed between an annular shoulder 53 in casing A and an annular disc 54. The ring 51 is slotted transversely at 55. The pawl lever 21b has a projecting tooth 56 which extends into the slot 55. The tooth has a "sloppy" fit in the slot in order to prevent it from binding within the slot when the pawl lever 21b is oscillated about its pivot. Stop lug 33b limits retractive movement of the pawl lever. The pawl lever is oscillated into and out of engagement with the ratchet wheel by means of the frictional resistance set up when the ring 51 is rotated within the channel 52.

Having thus described my invention, what I claim is:

1. An engine starting device comprising a stationary casing, a rotatable member, an engine shaft, an engine shaft engaging element pivotally connected to the rotatable member and rotatable therewith, said element being adapted to establish engagement with the engine shaft upon rotation of the rotatable member in engine starting direction, means associated with said element whereby upon reversing the rotation of said rotatable member, the element releases from engagement with the engine shaft, said means comprising an annular ring loosely mounted and rotatable relative to the stationary casing and having slight frictional engagement with the stationary casing, said element having engagement with the ring and being actuated thereby about its pivot.

2. An engine starting device comprising a stationary member, a rotatable member, an engine shaft, an engine shaft engaging element pivotally connected to the rotatable member and rotatable therewith, said element being adapted to establish engagement with the engine shaft upon rotation of the rotatable member in engine starting direction, means associated with said element whereby upon reversing the rotation of said rotatable member, the element releases from engagement with the engine shaft, said means comprising an annular ring having frictional engagement with the stationary member but being rotatable relative thereto, said ring having a projection adapted to engage an opening in the element whereby to actuate the element about its pivot.

3. An engine starting device comprising a stationary member, a rotatable member, an engine shaft, an engine shaft engaging element pivotally connected to the rotatable member and rotatable therewith, said element being adapted to establish engagement with the engine shaft upon rotation of the rotatable member in engine starting direction, means associated with said element whereby upon reversing the rotation of said rotatable member, the element releases from engagement with the engine shaft, said means comprising an annular ring having frictional engagement with the stationary member but being rotatable relative thereto, said ring having a recess in its periphery adapted to receive one end of said element, whereby to actuate the element about its pivot.

4. An engine starting device comprising an en-

gine shaft, a stationary casing, a rotatable pulley, a rope coiled thereon and fastened thereto at one end, a coil spring having connection with the pulley, whereby upon rotation of the pulley 5 in one direction the spring stores energy, said energy being utilized to rotate the pulley in reverse direction, a ratchet wheel secured to the engine shaft, a pawl pivotally connected to the pulley for engaging the ratchet wheel, whereby 10 rotation of the engine shaft in engine starting direction is effected, means connected to the pawl for maintaining the pawl in a position of disengagement relative to the ratchet wheel when the engine starts, said means comprising an annular ring loosely mounted and rotatable relative to the stationary casing and having operative connection with one end of the pawl, said ring also having slight frictional engagement with the stationary casing.

20 5. In an engine starting device including a stationary member and a rotatable member for imparting rotation to an engine shaft, means associated with the rotatable member for engaging the engine shaft, and an annular ring 25 associated with said means for effecting engagement and disengagement of said means with the engine shaft, said annular ring being loosely mounted in an annular channel in said stationary member and having slight frictional engagement 30 with the walls of said channel.

6. In an engine starting device including a stationary casing and a rotatable member for imparting rotation to an engine shaft, means associated with the rotatable member for engaging the engine shaft, and a ring-like member 35 associated with said means for effecting engagement and disengagement of said means with the engine shaft, said ring-like member being loosely mounted and rotatable relative to the casing, 40 whereby said ring-like member has slight frictional engagement with the casing.

7. In an engine starting device including a stationary member and a rotatable member for imparting rotation to an engine shaft, an element 45 associated with the rotatable member for engaging the engine shaft, a ring-like member, a looped projection on said ring-like member, said projection slidably engaging said element for effecting engagement and disengagement of 50 said element with the engine shaft, said ring-like member terminating in two free ends whereby to permit compressibility of said ring-like member, said ring-like member being movable relative to the stationary member and having sliding frictional engagement with said stationary member.

8. In an engine starting device including a stationary member and a rotatable member for imparting rotation to an engine shaft, an element associated with the rotatable member for engaging the engine shaft, a ring-like member, a looped projection on said ring-like member, said projection slidably engaging said element for effecting engagement and disengagement of 65 said element with the engine shaft, an annular face on said stationary member, a retaining member secured to the stationary member and spaced from the annular face, said ring-like member being loosely mounted between the annular face and the retaining member and having sliding frictional engagement with said face and retaining member.

W. L. GORDEN.
